CLAIM

The ornamental design for a data display for a settable controller, as shown and described.

DESCRIPTION

FIG. 1 is a perspective view showing the front, one end and one side of a data display for a settable controller showing our new design;

FIG. 2 is a front elevational view thereof;

FIG. 3 is a back elevational view thereof;

FIG. 4 is a side elevational view of an opposite side thereof; and,

FIG. 5 is an end elevational view of an opposite end thereof.
